UNITED STATES PATENT OFFICE.

JOHN HANSON, OF WORCESTER, MASSACHUSETTS.

WOODWORKING MACHINE.

1,422,971.

Specification of Letters Patent.

Patented July 18, 1922.

Application filed April 16, 1921. Serial No. 461,863.

To all whom it may concern:

Be it known that I, JOHN HANSON, a citizen of the United States, having taken out my first papers, residing at Worcester, in the county of Worcester and Commonwealth of Massachusetts, have invented a new and useful Improvement in a Woodworking Machine, of which the following, together with the accompanying drawings, is a specification.

My invention relates to wood working machines, and has for its object to provide an improved machine of the above described type, that is capable of carrying on a large number of the varied operations associated with wood working.

Further objects of my invention are to provide an improved wood working machine embodying first, a universal mounting for a rotating tool, whereby the tool may be placed in any desired position in order to operate upon the work; secondly, a novel form of work holding and feeding device, whereby the work may be conveniently moved with respect to the cutting tool; and thirdly, a novel form of support for a saw, whereby the latter may be conveniently positioned on the work supporting table. These and other advantageous features of my invention will hereinafter more fully appear, reference being had to the accompanying drawings, in which—

Figure 1 is a view in side elevation of a wood working machine embodying my invention.

Figure 2 is a view in end elevation of the machine shown in Fig. 1.

Figure 3 is a plan view of the machine shown in Fig. 1.

Figure 4 is a plan view of a portion of the parts shown in Fig. 3, illustrating my work holding and feeding device on an enlarged scale.

Figure 5 is a plan view of a modified form of work holding device, for use in connection with a saw.

Figure 6 is a transverse sectional view on the line 6—6, Fig. 4.

Figure 7 is an enlarged sectional view on the line 7—7, Fig. 1.

Figure 8 is an enlarged detailed view showing the clamp for the saw.

Figure 9 is a horizontal sectional view on the line 9—9, Fig. 8.

Similar reference characters refer to similar parts in the different figures.

Referring to Figs. 1 and 2, my machine

generally comprises a table 1, provided with suitable frame members 2, whereby the table 1 is supported a convenient height above the ground for the operator. A bracket 3 is located at one end of the table and is provided with a shank 4 extending downwardly below the table 1 and secured in position by suitable clamping members 5 and 6 cooperating with the end frame members 2. The upper portion of the bracket 3 is bifurcated and a socket member 7 is pivotally mounted between the arms 8 of the bifurcated portion on a pin 9 which extends through the arms 8 and a tongue 10 of the socket 7.

A shaft 11 is carried by the head 12 of the socket 7 and a frame 13 is pivotally mounted on the shaft 11 by means of lugs 14 through which the shaft 11 passes. A tool shaft 15 is rotatably mounted in lugs 16 provided at the other end of the frame 13 and is provided with a pulley 17 by means of which it may be rotated. The lower end of the shaft 15 terminates in a tool holder 18 within which is supported a suitable cutting tool 19. A lever 20 is pivotally supported at the upper end of the shaft 11 by a collar 21, and is connected to the shaft 15 by means of a link 22 which receives a threaded rod 23. As best shown in Fig. 7, the rod 23 terminates in a ball 24^a which is seated in a socket 24^b in the shaft 15. The lever 20 terminates in a handle portion, by means of which it may be turned about its pivot to move the shaft 15 vertically with respect to table 1, the ball and socket joint permitting universal movement of the rod 23. Stops 15^a are provided to limit the movement of shaft 15.

Driving pulleys 25 and 26 are rotatably mounted on an extension of the pivot pin 9 and the pulley 26 is connected to the pulley 17 by means of a continuous belt 27 which passes over a pair of guide pulleys 28, that are mounted on brackets 28^a carried by the head 12, and a second pair of pulleys 29 that are mounted on a bracket 29^a carried by the shaft 11. The pulley 25 is connected to any suitable source of power, not shown.

As best shown in Fig. 2, the head 12 of the socket 7 is provided with a pair of ears 30, between which is rotatably mounted a worm 31. The worm shaft 32 extends beyond the ears 30 and each end thereof is provided with a squared portion 33 for receiving a suitable operating handle 34, by means of which the worm 31 may be turned. The worm 31 is in mesh with a plurality of teeth

2

35, provided on one of the arms 8 of the bracket 3, the teeth 35 being arranged concentrically about the axis of the pivot pin 9. Turning of the worm 31 will therefore cause 5 the socket 7 together with the tool frame 13, to be swung about the axis of the pin 9, as indicated in dotted lines. The pin 9 is provided at one end with a fixed collar 36 in engagement with the pulley 25 and at 10 the other end with a lock nut 37, by means of which the tongue 10 of the socket 7 may be clamped between the arms 8 of the bracket 3, in order to secure the tool frame 13 in position after it has once been adjusted 15 by means of the worm 31. The shank 4 of the bracket 3 is provided with an arm 38 which terminates in an internally threaded portion 38^a through which extends a screw shaft 39. The shaft 39 is connected by bevel 20 gearing 40 to a handle 41 by means of which it may be turned in order to cause the bracket 3 to be moved vertically by reason of the connection between the shank 4 and the screw shaft 39. In this way the bracket 3 together 25 with the entire tool carrying structure can be located at any height above the table 1 and then be secured in position by the clamping members 5 and 6.

From the foregoing, it is apparent that I 30 have provided a universal mounting for the tool holder 18, whereby it may be positioned in any desired relation with respect to the table 1. In the first place, the frame 13 may be positioned at any desired height above 35 the table 1 by adjustment of the shank 4 through the screw shaft 39. The axis of rotation of the tool shaft 15 may then be fixed at any desired angle by turning the worm 31. After the frame 13 has been positioned 40 as described above, it may then be swung about the axis of the shaft 11 and lastly, the tool shaft 15 may be moved longitudinally on the frame 13 by means of the lever 20, a spring 20^a being provided to 45 assist in raising the lever 20 from its original position. In this way, the tool 19 may be initially positioned with any desired relation to the work which is adapted to be controlled by my improved work holding and 50 feeding device, which will now be described.

Referring now to Fig. 3, the table 1 is provided with a slot 42 along the sides of which are provided rails 43 for slidably supporting a plate 44, so that its top is flush 55 with the top of the table 1. A work support 45 is carried on the plate 44 and is provided with rollers 45^a and with a foot 46 through which it is secured to the plate 44 by a bolt 47 coating with one of several holes 60 48 provided in the plate 44.

A work holding and feeding device is also carried on the plate 44 and as best shown in Figs. 4 and 6, comprises a triangular shaped bracket formed by spaced plates 49. 65 The bracket is pivotally mounted on a pin 50

passing through the plates and held in position by a clamp 51 secured to the plate 44. A toothed wheel 52 is rotatably mounted between the plates 49 and each plate 49 is provided with a slot 53 for receiving a worm 54 which is 70 in mesh with the wheel 52. The worm 54 is carried on a shaft 55 mounted in bearings 56, one of which is adapted to be engaged by a disk 57 eccentrically mounted on a pin 58. The disk 57 is provided with a handle 75 59 by means of which it may be turned to engage the bearing 56, and thereby turn the bracket about its pivot 50 until the wheel 52 engages the work and forces it against the support 45. An adjustable stop 60 is carried by the plate 44 to limit the pivotal movement of the bracket and thereby prevent the wheel 52 from cutting too deeply into the work.

The shaft 55 is provided with a handle 85 55^a by means of which the worm 54 may be turned, and it is obvious that when the teeth of the wheel 52 are held in engagement with the work, turning of the worm 54 will cause the work to be moved either toward or away 90 from the tool 19, as shown in Fig. 3. The plate 44 is provided with a handle 44^a by means of which it may be moved back and forth on the rails 43 in order to properly position the work. The work support 45 is 95 adapted to be positioned at any desired angle on the plate 44, so that the line of movement of the work as it is fed will be substantially tangential to the periphery of the cutting tool, or in any other desired relation thereto. The work support 45 may also be shifted on the plate 44 and secured in a new position by employing the other holes 48.

Referring again to Fig. 1, a circular saw 61 is rotatably mounted in bearings 62 provided on an arm 63. The arm 63 is pivotally mounted on a pin 64 supported at one end of the frame and the other end of the arm 63 projects beyond the opposite end of the table 1. As best shown in Figs. 8 110 and 9, the arm 63 extends between the flanges 65 of a pair of vertical frame members 66. The arm 63 is adapted to be clamped between the flanges 65 in any desired position, by means of a clamping member 67 which embraces the flanges 65 and is adapted to force them together by means of a stud 68 provided with a handle 69. In this way the saw 61 may be so positioned that its periphery will extend through a 120 slot 70 provided in the table 1, the desired amount. The lower portion of the clamp 67 is provided with a pin 71 for supporting the arm 63. The shaft 72 of the saw 61 is provided with a pulley 73 that is 125 connected to driving motor 74 by means of a belt 75 passing over pulleys 76 and 77, mounted on a bracket 78.

Referring now to Fig. 5, a plate 79, similar to the plate 44 is provided with a work 130

support 80, to which it is secured by means of a bolt 81 coating with one of several holes 82. A screw shaft 83 is rotatably mounted on a lug 84 extending upwardly 5 from the surface of the plate 79 and is adapted to be turned by means of a handle 85. The end of the shaft is provided with a work engaging head 86 which is adapted to hold the work firmly in engagement with 10 the support 80. The work is adapted to be moved with respect to the saw 61 by sliding the plate 79 on the rails 43 and the support 80 is adapted to be secured in any desired position to obtain the proper angle 15 of cut, when the work is engaged by the saw.

From the foregoing, it is apparent that I have provided a wood working machine that is particularly adapted to perform a 20 large number of operations associated with wood working. Thus, a given piece of rough stock may first be planed by the tool 19 by the use of the work feeding device, it being obvious that any desired depth of 25 cut may be obtained by properly positioning the plate 44. It is also obvious that the axis of the tool 19 may also be changed to plane a bevel surface, if so desired. A boring tool may then be substituted for the 30 planing tool and holes drilled into the work at any desired angle by manipulating the handle 20 and raising and lowering the tool shaft 15. It is also obvious that many other operations may be performed upon 35 the work by employing various other tools and by moving the work holder to different positions. The saw 61 may also be arranged for any desired depth of cut by clamping the arm 63 between the flanges 65 so that 40 the saw will project above the table the required amount. The work may then be fed to the saw by means of the plate 79 as previously described.

It is obvious that my machine is adapted 45 for a great variety of work and that it may be advantageously employed wherever wood working is being carried on in place of the cumbersome carpenters' benches and hand tools heretofore employed. 50 While I have shown my universal tool holding frame as applied to a wood working machine, it is not so limited, for it is obvious it may as well be applied to other machines employing a rotating tool, and I 55 desire therefore that only such limitations be imposed thereon as come within the scope of the appended claims.

I claim:

1. In a machine of the class described, a table, a bracket provided with a shank 60 vertically adjustable on said table and terminating in a head, a socket turnable on a horizontal pivot pin extending through said head and a shaft extending from said socket upon which is pivotally mounted a tool 65 carrying frame.

2. In a machine of the class described, the combination with a work table, a vertically adjustable bracket; a support mounted on said bracket for adjustment about a horizontal axis, and a frame pivotally mounted on said support for free swinging movement, of a tool shaft carried by said frame and adapted for movement along its longitudinal axis. 75

3. In a machine of the class described, a table, a bracket, provided with a shank vertically adjustable on said table and terminating in a head, a socket turnable on a horizontal pivot pin extending through 80 said head, a worm and gear for adjusting the position of said socket on said head, and a shaft extending from said socket upon which is pivotally mounted a tool carrying frame. 85

4. In a machine of the class described, the combination with a work table, a support mounted on a horizontal pivot pin carried by said table, a driving pulley mounted on said pin and a frame pivotally 90 mounted on said support for free swinging movement, of a tool shaft carried by said frame and adapted for movement along its longitudinal axis, and a belt connecting said tool shaft to said pulley. 95

5. In a machine of the class described, the combination with a table, a tool carrying frame pivotally mounted on said table, a plate slidably mounted on said table and a bar positioned on said plate, of frictional 100 means for holding a piece of work against said bar and for moving it back and forth thereon with respect to said tool frame.

6. In a machine of the class described, the combination with a table, a tool carrying frame pivotally mounted on said table, a plate slidably mounted on said table and a bar positionable on said plate, of a toothed member rotatably and pivotally mounted on said plate, means for moving said member 105 about its pivot to hold a piece of work against said bar, and means for rotating said member to cause movement of the work. 110

JOHN HANSON.
